UNITED STATES PATENT OFFICE.

WALTER C. RUNGE, OF CAMDEN, NEW JERSEY, ASSIGNOR TO ROYAL PHONE AND PHONOGRAPH COMPANY, OF BOSTON, MASSACHUSETTS, A CORPORATION OF MAINE.

APPARATUS FOR FORMING IMPRESSIONS ON PHONOGRAPH-RECORD BLANKS AND LIKE ARTICLES.

1,018,631.

Specification of Letters Patent. Patented Feb. 27, 1912.

Application filed April 21, 1909. Serial No. 491,223.

To all whom it may concern:

Be it known that I, WALTER C. RUNGE, a citizen of the United States, and a resident of the city of Camden, county of Camden, 5 and State of New Jersey, have invented certain new and useful Improvements in Apparatus for Forming Impressions on Phonograph-Record Blanks and Like Articles, of which the following is a specification.

10 My invention does not relate to the making of the blanks for phonograph records and like articles, but to the forming or impressing upon or into the same, of projections or recesses for the tune or other matter which is to be reproduced from the record.

I will describe an apparatus used in carrying out my invention, and then enumerate the novel features in claims.

20 In the accompanying drawings: Figure 1 is a vertical elevation partly in section, of an apparatus suitable for use in carrying out my invention. Fig. 2 is a top view of a tank and appurtenances comprised in the apparatus. Fig. 3 is an inverted or bottom view of the tank and appurtenances. Fig. 4 is a side view of a segment of an expander comprised in the apparatus. Fig. 5 is a transverse section of this expander. Fig. 6 is a 25 longitudinal section of certain parts of a modified form. Fig. 7 is a side view of an apparatus for ejecting the expanders. Fig. 8 is an enlarged longitudinal section of parts shown also in Fig. 1. Fig. 9 is a central 30 transverse section of these parts. Fig. 10 is a longitudinal section of parts of an expander. Figs. 11, 12 and 13 are views illustrating means whereby the expander is caused to exert pressure first at its middle 35 portion and from there progressively toward the ends; Fig. 11 showing a longitudinal section of the parts, on a larger scale than the previous views, and with the mandrel G out of engagement with the staves of 40 the expander, which latter are shown as curved or bowed; Fig. 12 is a detail elevation of one of these expander staves showing in full lines the normal or bowed condition of said stave and showing in dotted lines the 45 straightened out condition of such stave, produced by the action of the mandrel; and Fig. 13 is a fragmentary top view of one of 50

the caps c⁷, showing the openings c⁹ therein for the escape of air.

Similar letters of reference designate corresponding parts in all the figures.

The apparatus comprises a press which may be of any suitable form, having cylinders A and pistons provided with protruding rods B operated by fluid supplied by a pipe a¹ under control of suitable valve mechanism a². These cylinders and pistons may be of any suitable number. Preferably they will be operated independently to the extent that each may act upon the part 60 which it is to operate to any degree that may be important, without requiring any other to operate to the same degree.

C designates a tank, here shown as of polygonal form, and provided with an inlet 70 c¹ and an outlet c². Extending between its top and bottom walls are tubes c³ which at their lower ends are shown as fitting into rabbets or recesses c⁴ formed in the bottom wall of the tank, with an interposed packing c⁵ of any suitable material to make a tight joint, and which at the upper end are shown as secured within openings c⁶ formed in the top wall of the tank by means of caps c⁷ provided externally with screw threads 75 80 engaging with the top wall of the tank and having inwardly turned flanges overlapping the upper ends of the tubes, a suitable packing being preferably used between these parts to prevent leakage. The caps and 85 tubes may be integral. It will be seen from this description that a fluid hot or cold, may by means of the inlet and outlet c¹ and c², be circulated through the tank around its 90 various tubes c³.

The tubes c³ are either made to constitute matrices or else are provided with matrices. In the present instance they constitute matrices by themselves, being formed upon their inner surfaces so as to constitute negatives 95 of records which are to be impressed upon phonograph cylinders or like articles.

Within the tubes c³ are tubular expanders D more particularly shown in Figs. 4 and 5, and these are so constructed as to be expandable for the purpose of forcing a record blank E which is introduced between each of them and the corresponding tubes c³ into the matrix of the latter. The bottom of the

tank C forms a stop for the tubular expanders D, preventing said expanders from moving longitudinally and so preventing stripping of the record blank E by longitudinal motion of said blank after it has engaged the surface of the matrix. This expander D may be composed of any suitable number of longitudinal sections d^1 severally forming segments of a tube. In the present instance 10 there are twelve of such sections and they are secured together by springs d^2 at their longitudinal edges, but in such manner that adjacent segments may move toward and from each other. As here shown the springs 15 d^2 are bow shaped and engage with pins d^3 inserted in the sections d^1 and crossing recesses into which the middle portion of the springs extend but so that the ends of the springs may extend into recesses d^4 formed 20 in the next adjacent sections d^1 . If found necessary, where records are to be formed upon thin material, the segments d^1 of each expander D may have a surrounding sleeve F (see Fig. 6) of soft india rubber or similar material to prevent the edges of the sections d^1 from forming ridges or grooves upon the material in which the record is to be made.

With each expander D a mandrel G is 30 combined. It is longitudinally tapered and the inner surface of the expander D with which it is to coact, is similarly tapered so that when a mandrel G is forced longitudinally into an expander D the latter will be 35 forced outwardly in a circumferential direction and therefore will force into the matrix of the corresponding tube c^3 the material of a record blank E.

It will be understood that each cylinder 40 A and piston B constitute an engine. There may be as many of these engines as there are tubes c^3 and coacting parts in a tank C so that when such a tank is pressed upon the bed of a press in such position that its mandrel G will be under the piston rods of the engines, the operation of the engines will cause the mandrels to move longitudinally in the proper direction to expand the expanders D and force the record blanks E 45 outwardly into the matrices of the tubes c^3 .

Before the mandrels G are operated in the manner just described, the tank is supplied with a heating medium which will preferably be hot water introduced through 55 the inlet c^1 and maintained in the tank for a time long enough to make the record blanks sufficiently plastic to receive clear and well defined impressions from the matrices of the tubes c^3 . After the removal of a tank C 60 from the press, a cooling medium is to be introduced into it and this may be cold water. If the cold water is introduced through the inlet c^1 it will force out the hot water and afterward cool the finished records so that they 65 will be disengaged circumferentially from

the matrices by contraction. The mandrels G will then be removed. This may be done by a separate press H (see Fig. 7) having pistons movable upward into holes c^8 in the bottom of the tank and concentric with the tubes c^3 . A separate press is, however, unnecessary because the tank may be turned upside down if its bed is provided with suitable holes, and the pistons B acting upon the smaller ends of the mandrels G may 70 then be used to eject the mandrels. After the removal of the mandrels G the contracted expanders D may be taken out and afterward the finished records E may be 75 removed.

Whenever different matrices c^3 are to be used in a tank, the previously used ones may be removed by detaching the caps c^7 . Afterward by a reversal of the described operations new matrices may be secured in the 80 tank.

By having for each press several tanks of the kind described supported on slideways J, it will be possible to get one ready for the press while a second is in the press and 85 while a third is having finished records removed from it. They may be moved along slideways J.

I have shown one of the piston rods as provided with an equalizing bar b^1 which is 90 pivoted between its ends by a pin b^2 to the piston rod, and made of sufficient length so that its ends may impinge upon two of the mandrels G. By this means the number of engines is reduced to one half what would 95 otherwise be necessary and withal an independent operation of each mandrel of a pair is secured.

In Fig. 6 I have shown two mandrels g^1 and g^2 tapering longitudinally toward their 100 adjacent ends and with them is combined an expander D^1 which tapers from each end toward the center. These mandrels will each be operated in the same manner as the single mandrel comprised in the main example of my invention.

To insure escape of air, the segments of the expanders are preferably longitudinally bowed, as indicated particularly in Figs. 11 and 12, so that when the taper mandrel G, 115 in its descent, acts upon said segments or staves, these segments first act upon the record blank near the middle thereof, and thence act thereon progressively toward the ends, thereby forcing out any air which may 120 be between the expander and the record.

The caps of the matrix tubes c^3 may be provided with holes c^9 for escape of air, and there may be radially arranged air escape recesses c^{10} in the upper surfaces of 125 the rabbets c^4 .

What I claim is:—

1. A tubular matrix, a container therefor, a tubular expander arranged within the matrix, said matrix container forming a stop 130

- for said expander preventing longitudinal motion thereof, and a mandrel arranged within the expander, all being so combined that a record blank for a phonograph or like article may be arranged between the matrix and expander, and that the mandrel by acting on the expander may produce pressure for forming a record upon the record blank.
- 5 10 2. A tubular matrix, a container therefor, a tubular expander made of a number of longitudinal sections yieldingly connected together and arranged within the matrix, said matrix container forming a stop for 40 said expander preventing longitudinal motion thereof, and a mandrel arranged within the expander, all being so combined that a record blank for a phonograph or like article may be arranged between the matrix and the expander, and that the mandrel may produce pressure for forming a record upon the record blank.
- 15 20 3. A tubular matrix, a tubular expander made of a number of longitudinal sections made of resilient material, formed so as to be normally protuberant externally intermediate of their ends, yieldingly connected together and arranged within the matrix, and a mandrel arranged within the expander, all 45 being so combined that a record blank for a phonograph or like article may be arranged between the matrix and the expander, and that the mandrel may produce pressure for forming a record upon the record blank.
- 25 30 4. A tubular matrix, a container therefor, a tubular expander made of a number of longitudinal sections connected together at their adjacent edges by springs and arranged within the matrix, said matrix container 50 forming a stop for said expander preventing longitudinal motion thereof, and a mandrel arranged within the expander, all being so combined that a record blank for a phonograph or like article may be arranged between the matrix and the expander, and that the mandrel may produce pressure for forming a record upon the record blank.
- 35 40 5. A tubular matrix, a container therefor, a tubular expander made of a number of longitudinal sections surrounded by an elastic sleeve and arranged within the matrix, said matrix container forming a stop for 55 said expander preventing longitudinal motion thereof, and a mandrel arranged within the expander, all being so combined that a record blank for a phonograph or like article may be arranged between the matrix and the expander, and that the mandrel may produce pressure for forming a record upon the record blank.
- 25 30 6. A tubular matrix, a container therefor, a tubular expander arranged within the matrix, said matrix container forming a stop for 60 said expander preventing longitudinal motion thereof, and a longitudinally tapering mandrel arranged within the expander, all being so combined that a record blank for a phonograph or like article may be arranged between the matrix and the expander, and that the mandrel may produce pressure for forming a record upon the record blank.
- 35 40 7. In testimony whereof I have signed this specification in the presence of two subscribing witnesses.
- 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580
